COLLAPSIBLE TUBE CLOSURE

Edward A. Tappe, San Bernardino, Calif.

Application November 6, 1931. Serial No. 573,330

1 Claim. (Cl. 221—60)

This invention relates to and has for an object the provision of a closure for collapsible tubes such as are employed as containers for shaving cream, tooth paste, ointments, etc., and a particular object is to provide a closure in the neck of a tube which will be self-contained within the tube, opened when pressure is applied to the tube for dispensing the contents of the tube, and self-closing when the pressure on the tube is relieved.

Having in mind a closure of the broad general characteristics hereinabove mentioned, it will be obvious that such a device is capable of many modifications and variations.

I have shown in the accompanying drawing, however, several different forms of device for carrying out the objects of this invention, from a consideration of which other forms will readily occur to those skilled in the art.

In said drawing, Fig. 1 is a perspective view of a collapsible closure applied thereto.

Fig. 2 is an enlarged fragmentary elevation showing an orifice in the neck of the tube by means of which the material from the tube may be dispensed in a ribbon-like form.

Fig. 3 is a fragmentary cross section of the same.

Figs. 4, 5 and 6 are transverse fragmentary sections of the outlet end of a collapsible tube such as is shown in Figs. 1 and 2, illustrating different forms of closures.

Fig. 7 is a fragmentary end view of a form of closure shown in Fig. 6, together with a portion of the tube.

In the consideration of this invention it will be understood that collapsible tubular containers A, such as is shown in Fig. 1, are formed of thin flexible metal and are permanently closed at an end 1, while the opposite end 2 is provided with a neck of reduced size onto which internally threaded caps (not shown) are usually screwed for closing and sealing the container. Such caps are frequently lost and must be detached and attached each time material is dispensed from the tube, thereby causing a loss of the material when the cap is lost, and if too long exposed to the atmosphere, a hardening of the material in the outlet orifice which renders further dispensing of the material difficult if not impossible at times.

The purpose of this invention is, therefore, to overcome the aforementioned difficulties by the provision of a self-contained and permanently attached closure B to the neck 3 of the tube A. Such a result can be attained satisfactorily by

methods illustrated and others which are not shown or described herein. For instance, as shown in Figs. 2 and 3, I may provide the closure B of button-like circular form with its periphery 4 slidably fitted into a bored or cored recess 5 at 60 the end of the neck 3, and normally adapted to rest on a shoulder 6 formed by providing an annular enlargement 7 within and intermediate the extremities of said neck. The outer portion of the neck is provided with a rectangular orifice 8 65 which is normally closed by the member B. The neck is provided inwardly of the annular portion 7 with a cored recess 9 in which a coiled spring C is supported upon a shoulder 10. The innermost turn of the spring C is bent to provide a radial 70 portion 11 and said radial portion is bent to provide an axial portion 12 which is bent at right angles from the portion 11 and is provided with a loop 13 adapted to hook into or over a lug 14 formed on the inner side of closure B. 75

Thus the spring C is compressed when the closure B is forced outwardly by the application of pressure to the tube A, and the tension of said spring serves to hold the closure firmly seated on the shoulder 6 for closing the orifice 8. 80

The form of closure shown in Fig. 4 is slightly different from that shown in Fig. 3 in that the closure B is provided with a beveled periphery 15 adapted to seat in a correspondingly beveled opening 16 formed in the outer end of neck 85 3 after the manner of a poppet valve and its seat. In this type of closure the annular portion 7 is omitted from the neck and a shoulder 17 is provided immediately below the closure B. The spring C seats against the shoulder 17 90 and is of the same type as the spring of Fig. 3.

The form of device shown in Fig. 5 differs from the other form described only in that the closure is of ball-like form and the outer end of the neck is curved, as shown, while the opening 18 95 therein conforms to the surface of the ball-like closure B.

The form of closure shown in Fig. 6 is similar to the form illustrated in Fig. 4, but the spring C is of different type. In this form of device a 100 spring of rectangular or circular cross section may be employed with a plurality of convolutions resting against the curved end portion 2 within the body of the tube rather than in the neck, as in the other types of closures. The spring is 105 connected with the closure B by means of an axial portion 19 hooked into an elongated stem 20 extending inwardly from the closure.

It will be observed that with the exception of the form of closure shown in Figs 2 and 3, 110

all of the closures are arranged to exude or dispense material from the tubes thru the central end opening, as at 16, in the neck around the periphery of the closure B. Thus when the body 5 of the tube A is squeezed by hand pressure thereon the spring C in each form of device is compressed and the closure B is forced outwardly, thus providing space around the closure as in forms shown in Figs 4, 5 and 6, or opening the 10 orifice 8 as in the form of device shown in Fig. 3, whereby the material may be dispensed from the tube.

When, however, the pressure on the tube is relieved the tension of the spring C in each case 15 serves to retract and firmly seat the closure B in the tube, thus preventing leakage or hardening of the material, which is occasioned by exposure to the atmosphere, and the closure in each case forms a sanitary seal for the tubes.

20 It will be apparent from the foregoing descrip-

tion of my invention that I have provided a simple, economical and efficient self-closing seal or cap for a tube of the character described, the structure and arrangement of which is subject to modification within the scope of the appended 8 claim without departing from the spirit thereof.

What I claim is:

A device of the class described, comprising a dispensing tube including a neck having a delivery opening therethru and a valve seat encircling said opening, a shoulder on said neck within said delivery opening, a valve associated with said seat, and a helical spring disposed within said delivery opening, one end of said spring engaging said shoulder and the other end 90 passing axially upward thru the helix formed by said helical spring and being connected to said valve to press the valve onto said seat.

EDWARD A. TAPPE.
